UNITED STATES PATENT OFFICE.

WILLIAM H. HAWS, OF JOHNSTOWN, PENNSYLVANIA.

METALLIC RAILWAY-TIE.

1,179,307.

Specification of Letters Patent. Patented Apr. 11, 1916.

Application filed November 13, 1915. Serial No. 61,300.

To all whom it may concern:

Be it known that I, WILLIAM H. HAWS, a citizen of the United States, residing at Johnstown, in the county of Cambria and State of Pennsylvania, have invented certain new and useful Improvements in Metallic Railway-Ties, of which the following is a specification.

This invention relates to an improved metallic tie for railways, and has for an object to provide a relatively light, simply constructed tie, comprising but few parts, which are so formed and assembled as to produce a device which may be easily and economically manufactured.

Another object of this invention is to provide a tie with fastening devices for engaging the rails, which will securely hold the rails to the tie, and will not become loosened or detached by vibration, and which may be taken up or tightened incident to wear, contraction, or the settling of the rails and the tie.

A further object of the invention is to provide a tie which supports the rail substantially flat upon the road bed, so as to admit considerable clearance between the tops of the cars passing over the rails and bridges, tunnels, roofs of mines, and the like, so that the railway may be introduced into relatively small spaces where ordinary railways cannot be used, on account of the height of the rails above the road bed.

Other objects and advantages of this invention will be clearly brought out in the following description of the present preferred embodiment of this invention, the same being illustrated in the accompanying drawings, wherein:

Figure 1 is a top plan view of the improved tie, having rails secured thereto. Fig. 2 is a longitudinal section on the line 2-2 of Fig. 1, looking in the direction of the arrow. Fig. 3 is a longitudinal section through the tie and rail, taken on the line 3-3 of Fig. 1. Fig. 4 is a transverse section, taken through one of the fastening devices and the tie on the line 4-4 of Fig. 1, showing the abutting ends of adjacent rails secured in place. Fig. 5 is a transverse section through one of the fastening devices on the line 5-5 of Fig. 1. Fig. 6 is a transverse section through one of the abutments or guides of the fastening device, taken on the line 6-6 of Fig. 3. Fig. 7 is a detail bottom plan view of the bed plate of the tie.

Fig. 8 is a detail under side perspective view of one of the abutments or guides employed. Fig. 9 is a detail perspective view of the spreading pin or wedge, showing the permanent locking means therefor. Fig. 10 is a detail perspective view of the spreading pin showing the adjustable locking means therefor. Fig. 11 is a detail perspective view of the locking key for coöperation with the spreading pin of Fig. 10.

Referring to the drawings, wherein like parts are designated by similar characters of reference throughout the several views, 15 designates the bed plate or body of the tie, which is formed of metal, has a substantial width, and is of the standard length of a tie. This bed plate 15 is provided with depending flanges 16 adapted to engage in the road bed to hold the tie from displacement.

The tie is provided near each end with a pair of rail engaging members. One member of each pair is preferably permanently secured in place prior to the placing of the tie beneath the rails, while the other member of each pair is adapted for adjustment against the rails after the tie is in position. For each rail engaging member there is provided in the bed plate 15, a slot 17. These slots 17 are arranged in slightly spaced relation, and in pairs, near the opposite ends of the bed plate, as clearly shown in Fig. 7. The slots 17 extend transversely across the upper face of the bed plate to a point near the lateral edges thereof. Each slot is provided with an enlargement or recess 18 intermediate each end thereof. These recesses 18 thus constitute elongations of the slot 17 at the middle thereof and provide retaining shoulders 19 at the corners of the slot. The rail engaging members are all of substantially the same construction, each one comprising an abutment or guide 20, of substantially T shape in cross section, the depending web 21 of which is adapted for insertion downwardly through the slot 17 and is of slightly less length than the body of the guide 20.

The web 21 is of such length that the ends thereof pass freely through the recesses 18. The ends of the web 21 are transversely recessed as at 22 to receive the shoulders 19 at the ends of the slot 17 and to provide retaining lugs 23 for engagement against the under side of the bed plate 15. As shown to advantage in Figs. 3 and 8, each abutment or guide is shouldered in its outer side

as at 24, which shoulder faces downwardly and is adapted to seat upon the top of the bed plate 15 along the edge of the slot 17. Thus, the abutment or guide is held in up-right position. The inner edge of the guide 20 is provided with an undercut slot 25 for a purpose which will hereinafter appear.

The rail engaging member also comprises 10 a clamping plate 26 of substantially T form in cross section. The depending web 27 of the clamping plate is shorter than the body of the plate for free passage through the recesses 18 and the slot 17, and is transversely 15 recessed or slotted at its opposite ends to receive therethrough the shoulders 19 at the corners of the slot 17. The ends of the web 27 are provided with lugs 28 engaging the underside of the bed plate 15 to retain 20 the clamping plate from lifting upward. The inner side of the clamping plate 26 is provided with an undercut slot 29, corresponding to the slot 25 in the abutment or 25 guide member 20, and extending substantially in parallelism and in spaced relation thereto. The outer side of the clamping plate has an overhanging flange 30 adapted to seat upon the rail base, the flange 30 being of any desired width and configuration 30 to engage more or less of the rail which seats upon the bed plate.

For the purpose of binding the clamping plate 26 against the rail, a spreading pin 31 is employed, the same being positioned 35 between the abutment or guide 20 and the clamping plate 26, and being of slightly wedge form whereby to separate the clamping plate 26 from the abutment 20 and bind the clamping plate against the base of the 40 rail. This spreading pin is of substantially inverted T shape in cross section, the T head fitting in the undercut slots 25 and 29 of the abutment 20 and the clamping plate 26 respectively. The pin 31 fits between the 45 adjacent sides or edges of the members 20 and 26 and as the body portion of the pin 31 is wedge shaped, or is tapered from end to end, it bears against the adjacent inner edges of the members and forces the same 50 apart. The abutment 20, as shown in Fig. 3, lies against the outer side of the slot 17 and cannot be moved outwardly. The slot 17, however, is enlarged laterally to extend appreciably beneath the rail base to admit 55 of the movement of the members 26 toward and from each other to accommodate rail bases of various widths. Thus, the clamping plate 26 of each of the rail engaging members is free to move forwardly toward 60 the rail, and as the pin 31 works against the fixed abutment or guide 20, the clamping plate 26 alone is moved and caused to bind against the rail base. As the clamping plate 26 is held from upward movement by the 65 lugs 28, which bear against the under side

of the bed plate 15, and as the lugs 28 are relatively narrow, as shown, the top of the clamping plate 26 is tilted inwardly toward the rail base, by the action of the pin 31 and caused to bind downwardly as well as 70 inwardly upon the rail base.

The spreading pin 31 is of a length slightly greater than that of the members 20 and 26, and is adapted to extend at its opposite ends beyond the longitudinal edges 75 of the bed plate 15. The reduced end of the pin 31 is provided with means for holding it in position after it has been driven into place. As shown in Figs. 1 and 9, this retaining means for the pin 31 is in the form 80 of a key 32 projecting from the head of the member 31, and being coextensive therewith. The key 32, which is of tongue shape, is flat and is adapted to be bent, by blows of a hammer or the like, down into the position 85 shown in Fig. 4 for engagement with the edge of the bed plate 15 to hold the pin 31 from withdrawal. This form of key 32 is what may be termed in the present instance, a permanent fastener for the spreading pin 90 31. The key 32 is adapted for use in positioning one of the rail engaging members of each pair prior to the application of the tie to the rails, so that a fixed gage may be measured upon the tie before it is placed in 95 the road bed.

After the tie is in position, and the rail is placed thereon beneath the overhanging flange 30 of the corresponding rail engaging member of each pair, the opposed members 100 20 and 26 are inserted through the opposite slots 17, and the opposite spreading pin 31 is driven into position. The spreading pin 31 is driven in until the rail engaging members 105 tightly bind against the opposite edges of the rail base so as to firmly hold the rail upon the tie. After the desired adjustment has been made, a locking key 33 is adjusted to hold the second spreading pin in place. As shown in Figs. 1, 5 and 10, the projecting reduced end of the spreading pin 31 is 110 provided in its body portion and in its flange or head, with registering transverse and vertical slots or recesses 34, spaced apart longitudinally of the pin a sufficient distance to 115 take up various adjustments of the pin. The key 33 is of inverted U shape and is adapted to be inserted downwardly into the slots 34, and is of such width as to abut the 120 adjacent extremities of the members 20 and 26. The lower ends 35 of the key 33 extend below the spreading pin 31 and against the adjacent edge of the bed plate 15. These ends 35 are adapted to be clenched or turned 125 inwardly, as shown in Fig. 2, to prevent the lifting of the key 33 out of the slot 34. Thus, when the pin 31 is driven into place, the slotted end thereof projects laterally 130 from the tie, and after the adjustment is secured, the key 33 is dropped downwardly

through the innermost exposed slot 34, and is clenched as above described so as to prevent the accidental removal of the key by vibration, or the like.

5 Of course, it is understood that the spreading pins 31 may all be provided with the locking means 33 and 34, or these spreading pins may all be provided upon their reduced ends with the tongues 32. In the

10 present instance, however, it is preferred to use the tongues 32 on the pins 31 of the permanent rail engaging members of each pair, and to use the key 33 and slots 34 in the opposite member of each pair to take up the various adjustments required in setting the rails, and also, during use, to take up all looseness incident to the settling of the rails and tie, the expansion and contraction of the parts, and the like.

20 It is, of course, understood that this improved tie may be used in connection with steam or electric roads, or may be used in smaller railway construction, such as for mine use. In the latter use this improved

25 tie is of particular advantage in that the rails lie substantially flat upon the ground or road bed, and thus a greater clearance is had between the tops of the cars and the roof of the mine. Also, the railroad may be introduced into relatively low tunnels, and beneath other structures where the relatively high ties preclude the use of the railroad.

30 The outer side of the spreading pin 31 is slightly inclined to produce the taper of the pin, and the adjacent inner edge or side of the abutment 20 is correspondingly inclined to bear uniformly against the inclined side of the pin 31, and thus effect the uniform pressure of the clamping plate 40 throughout its entire length.

45 It is, of course, understood that various modifications and combinations may be made with respect to the above described parts, such changes being restricted only by the scope of the following claims.

50 In the drawings, there is shown the abutting ends of adjacent rails resting across the improved tie. It will be noted that no fish plates, bolts or other rail joint devices are employed for holding these meeting ends of the rails together. The construction of the rail engaging members is such that the clamping plates engage uniformly throughout their length against the bases 55 of the rails and thus securely hold the same together. In railways, such as are used in mines, and wherein it is necessary to gradually advance the railway as the work proceeds, the tie of this invention is

60 particularly useful in that the tie may be placed across the extremities of the rails and when necessary additional ties may be inserted beneath the opposite or outer ends of the clamping members. The members 65 may then be tightened and the railway is

thus lengthened or advanced. The fastening member is composed of but three parts, the abutment, the clamping plate, and the spreading pin. These parts are of such construction that they may be quickly assembled upon the top of the bed plate and may be quickly adjusted to engage the rail.

What is claimed is:—

1. A metallic railroad tie, comprising a flat bed plate having a pair of slots adjacent each end, and a rail engaging member arranged over each slot for engagement against the opposite sides of a pair of rails, each member comprising a stationary abutment, a movable clamping plate, the abutment and the clamping plate each having a depending web for engagement in the slot beneath each rail-engaging member, and a spreading pin disposed between said abutment and said clamping plate to spread the same apart and secure the webs in the slots, and to bind the clamping plate against the adjacent side of a rail.

2. In a metallic railroad tie, a bed plate having a transverse slot in the upper side thereof, an abutment extending transversely across the top of the plate and having a depending web for engagement through said slot, retaining lugs carried upon the lower edge of the web for passage through the slot and adapted to engage the under side of said bed plate to hold the abutment in place, a clamping plate for engagement over the base of a rail and having a depending web passing down through said slot, retaining lugs on the web of said clamping plate to engage the under surface of said bed plate, and a spreading pin slidable across the top of the bed plate and engaging between said abutment and said clamping plate to move the latter against the rail base.

3. In a metallic tie, a bed plate adapted to be countersunk in a road bed, and pairs of rail engaging members at the opposite ends of said bed plate, each of said rail engaging members comprising an abutment detachably mounted on the upper face of the bed plate, a clamping plate slidably mounted on the bed plate and movable toward and from said abutment, and a spreading key interposed between the abutment and the clamping plate for binding the latter against the base of a rail.

4. In a metallic tie, a bed plate, an abutment detachably fixed upon the bed plate, a clamping plate slidably mounted on the bed plate and having an overhanging flange for engagement with the base of a rail, a spreading pin movable between said abutment and said clamping plate, and means for securing said spreading pin in position when adjusted.

5. In a railroad tie, a flat plate adapted to rest upon the road bed, pairs of spaced

4
apart abutments mounted upon the upper face of said plate, clamping plates slidably mounted upon said bed plate inwardly of said abutments and adapted for engagement with the opposite sides of a rail, spreading pins interposed between the abutments and the clamping plates for binding the latter against the rails, and keys on said spreading pins for locking the same in 10 adjusted position.

6. In a railroad tie, a flat plate adapted to be embedded in a road bed, an abutment, an interlocking web on said abutment for engagement with said bed plate to detachably hold the abutment across the upper face thereof, a clamping plate for engagement with a rail, an interlocking web on said clamping plate for slidable engagement with said bed plate to guide the clamping plate over the upper face of the bed plate, a spreading pin slidably mounted between the abutment and the clamping plate adapted to separate the same, and means for securing said spreading pin from withdrawal when adjusted.

7. A metallic tie, comprising a bed plate having a transversely extending slot in the upper face thereof and having a recess at each end of the slot, intermediate said end, 30 to provide an elongated passage through the middle of the slot, and contracted openings at the opposite sides of the slot, an abutment seated on the upper face of said plate and having a web depending into said slot and 35 provided with endwise extending lugs spaced beneath the abutment and adapted for engagement through the recesses, a rail clamping plate seated on top of said bed plate and having a web projecting down through said 40 slot and endwise extending lugs on the web spaced from the rail clamping plate, and a spreading member adapted for engagement between the abutment and the rail clamping plate to move the same apart and bind their 45 respective webs in the opposite sides of the slot.

8. A metallic tie comprising a flat plate adapted to be countersunk in a road bed, and pairs of rail engaging members mounted across said bed plate near the opposite ends thereof, said rail engaging members each comprising a detachable abutment extending across the bed plate, and having an undercut slot in its inner edge, a clamping plate slidably mounted on the bed plate for engagement with a rail and having an undercut slot in its inner edge, and a spreading pin interposed between said abutment and said clamping plate, and having lateral 55 flanges for engagement in said undercut slots whereby to hold the spreading pin from upward displacement.

9. In a metallic railroad tie, a bed plate having a transverse slot in the upper face 60 thereof, the bed plate also having recesses

at the ends of the slot and communicating with the slot intermediate each end thereof to provide elongations of the slot, an abutment adapted to seat upon the upper face of the bed plate, and having a depending web for engagement through the slot, lugs projecting longitudinally from the lower end of said web for passage through the recesses and for engagement beneath the under side of said bed plate laterally of the recesses, a clamping plate movable over the upper face of said bed plate and having a depending web for engagement through said slot, retaining lugs on the lower end of said web for passage through said recesses and 70 for engagement against the under side of said bed plate laterally of said recesses, and a spreading pin interposed between said abutment and said clamping plate to separate the same and retain said lugs out of 75 register with said recesses.

10. In a metallic railway tie, a bed plate having a transverse slot therein and recesses intermediate the ends of the slot, an abutment extending across said bed plate, a 90 clamping plate extending across said bed plate, said abutment and said clamping plate each having a depending web for engagement through the middle portion of said slot and said recesses, the webs being transversely slotted at their ends whereby to admit of the passage of the webs into the reduced sides of the slot, the lower portions of the webs below said transverse slots engaging against the under side of said bed plate 95 to retain the abutment and the clamping plate from upward movement, and means engaging said abutment and said clamping plate for spreading the same apart to hold said webs in the reduced sides of the slot, 100 and to move said clamping plate inwardly.

11. In a metallic railroad tie, a bed plate, an abutment extending transversely across the bed plate, a clamping member movable toward and from the abutment, a spreading 110 pin interposed between said abutment and said clamping member and having an extension upon the forward end thereof, said extension having a longitudinally spaced apart row of registering transversely and 115 vertically extending slots, and an inverted U-shaped flat key adapted for engagement in any one of said slots and for engagement flat against the side of the bed plate and the ends of the abutment and the clamping member, whereby to hold the spreading pin in 120 any adjusted position.

12. In a metallic railway tie, a bed plate having a transverse slot in the upper face thereof, the slot being formed with an intermediate elongated portion, a pair of members adapted to abut upon the upper face of said bed plate, and having depending webs for engagement through the elongated portion of the slot, said webs having 125 130

transverse recesses in their ends whereby said webs may be spread apart into the opposite reduced sides of the slot, and a spreading member engaging said first members to separate the same.

13. In a railway tie, a bed plate, a pair of rail-clamping members mounted upon each end of said bed plate, each of said members comprising a pair of movable parts, a spreading pin adjustable between each pair of parts, a permanent key secured to the spreading pin of a corresponding clamping member of each pair, and a detachable and adjustable key secured to the spreading pin of the other clamping member of each pair.

14. In a railway tie, a bed plate, a pair

of rail-clamping members on each end of the bed plate, each rail clamping member comprising two movable parts, a spreading pin between the parts, a permanent key for the spreading pin of a corresponding clamping member of each pair adapted for adjustment prior to the positioning of the tie beneath the rails, and an adjustable key for the remaining clamping member of each pair adapted for adjustment subsequent to the securing of the rails to the tie.

In testimony whereof I affix my signature in presence of two witnesses.

WILLIAM H. HAWS.
